CARD ATTACHING DEVICE

Filed Feb. 24, 1932

FIG. I.

FIG. II.

FIG. III.

INVENTOR:
George W Lentz,
BY Traley Paul
ATTORNEYS.

UNITED STATES PATENT OFFICE

GEORGE W. LENTZ, OF ENOLA, PENNSYLVANIA

CARD ATTACHING DEVICE

Application filed February 24, 1932. Serial No. 594,973.

My invention relates to devices for attaching placards to walls, such as the sides of freight cars or other objects, at points beyond the reach of a man standing on the ground.

In the handling of freight cars, for example, it is necessary that placards of various kinds be attached to their sides. Such placards are used to designate certain types of contents that require care in handling, such as explosives, corrosive liquids, acids, or the like. Routing cards are also attached to freight cars from time to time. When explosives are transported, it is customary to use cards bearing the word "explosive", and to affix such cards on the sides of the carrier four-and-a-half feet above the floor line by means of capnails. The disadvantages of the usual practice of carrying a ladder from car to car in order to attach cards in this manner are obviously of a serious nature, even in a small freight yard. Not only is it inconvenient and hazardous to use a step-ladder in the placing of placards on freight cars at the proper distance from the floor line, but it is no less hazardous for a man on the roof of a freight car to reach down to place a placard on the side of the car.

The principal object of this invention is to avoid the aforementioned difficulties by utilizing a tool which enables such placards to be handily and quickly applied from the ground level.

A more specific object of this invention is to provide in such a tool a card holder which will accommodate varying sizes of cards with equal facility, and which will so hold the cards, preparatory to their application, as to facilitate their ready positioning on the wall to which they are to be attached.

A further object of the invention is to provide a card holder capable of holding a card firmly in windy weather. This end I accomplish by the provision of card-holding means on the tool handle for engaging the bottom of the card, and by additional card-holding means on the tool head for gripping the upper edge of the card, said means be-

ing releasable, when the nail is driven, by a downward pull of the tool handle.

Still other objects and advantages characterizing my invention will be evident from the description hereinafter of one embodiment or example of the invention, the description having reference to the accompanying drawing, whereof:

Fig. I represents a side view of the card attaching device showing the manner in which a card is held thereby preparatory to its application to a wall.

Fig. II represents a top view of the card attaching device.

Fig. III represents an end view of the card attaching device.

With reference to the drawing, and particularly to Fig. I, there is shown a long metal tool handle 1 with a claw 2 at its lower end. This claw 2 is bent slightly to facilitate its function as a nail remover, it being frequently necessary to remove old tacks or nails before applying a placard to a wall. The other end of the handle 1 is threaded and is screwed into a nail-driving tool head 4. On the handle 1 there is soldered or welded a card holder 3 which comprises a stiff metal strip and forms with the handle a deep slot for the reception of a placard, such as indicated at A, the entrance to the slot being disposed under the head 4. As shown in Fig. I, the major portion of the card A is sheathed in this slot, and accordingly held against pressure of the wind.

A card retaining clip 5 is fastened to the top of the tool head 4 by a screw 6, one end of the clip 5 being engaged within a recess 7. The retaining clip 5 is made of resilient material sufficiently stiff to grip firmly the upper edge of the card A between itself and the head 4, while permitting the release of the card, after its application, by a sharp downward pull of the handle 1. The free end of the retaining clip 5 is preferably provided with a finger piece 8 for convenience in the positioning of a card on the tool head 4, and the retaining clip is directed toward the nail driving face 9 of the head 4.

A nail holder 10 is fastened to the underside of the head 4 by means of a screw 11,

the nail holder having a hole 12 through which the handle 1 passes. The nail holder 10 is further engaged between projecting lugs 13 on the face 9 of the tool head. The nail holder 10 is preferably made of a stiff heavy material which will hold its shape in spite of sharp blows, and which will not readily bend.

The nail holder 10 has a bifurcated free end affording a slot 14 within which the body of a nail, such as designated at B, is inserted. A groove 15 extends vertically across the face 9 of the tool head 4. The cross section of the groove 15 is preferably shaped to conform to the shape of the head of a capnail. The groove 15 is in alignment with the slot 14 of the nail holder 10, and together with the nail holder 10 affords a means of positioning a nail at right angles 15 to the face 9 and substantially in the center thereof, and hence in position for driving. The point of the nail B protrudes from the slot of the nail holder 10 toward the placard A. In an obvious manner the nail B is applied to the tool head 4 by inserting it with 20 its head in the groove 15 and sliding it downward through the open end of the nail holder slot 14. The free end of the nail holder 10 is spaced from the face 9 of the tool head and is curved to provide a surface 16 which substantially conforms with the curvature of the card A when applied to the tool. The opposite end of the tool head 4 is fashioned into a hammer face 17 25 for use in driving a nail home after it is started with the nail holder 10.

The operation of the tool or device of this invention is as follows: A nail, such as shown at B, is first placed as described 40 within the tool holder 10 with its point projecting outward. A card is then mounted on the tool head with its upper end engaged by the spring clip 5, and its major portion held against the tool handle by the card holder 3. Thereafter the operator swings the tool directing the nail driving face 9 toward the spot on the wall where the card is to be attached. With a sharp blow he drives the point of the nail into the car side. Then by a sharp downward pull 45 with the long handle 1, he disengages the nail head from the groove 15 and at the same time disengages the top edge of the card A from the spring clip 5, allowing the card to slide away from the holder 3. By taking care that the first nail is driven through the card A near its center line, the card will be positioned squarely upon the wall, and additional nails serve only to attach it 50 more securely. After each nail is applied, the tool may be reversed and the hammer head 17 may be used to drive the nail home.

It will be apparent from the above description that the construction and arrangement of the card holder 3 and clip 5 permit

the use of a comparatively wide range of card sizes with the tool of this invention. Furthermore, the pressure of the wind is resisted by housing the major portion of the card in the long slot between the handle 1 and the card holder 3; and there is little chance of the card slipping from the clip until nailed to the car side.

In contradistinction to certain previously proposed devices designed for generally similar purposes, the tool of my invention permits the ready application of a placard to the tool without the necessity of first piercing the placard at predetermined points with one or more nails.

While I have described my invention in some detail and with reference to a specific embodiment thereof, it will be evident that various changes may be made in the form of the apparatus disclosed without departing from the spirit of the invention as defined in the appended claims, and it will also be evident that certain features of the invention may at times be used to advantage without a corresponding use of other features of the invention.

Having thus described my invention, I claim:

1. In a card attaching device, a handle, a card holder on said handle, a nail-driving head on said handle, and a clip on the top of said head for engaging the top portion of the card while a nail is driven by said head.

2. In a card attaching device, a handle, a holder on said handle forming therewith a slot for the reception of a portion of a card, a nail-driving head on said handle, and a spring clip on the top of said head for engaging the top edge of said card while a nail is driven by said head.

3. In a card attaching device, a handle, a card holder on said handle, a nail-driving head on said handle including a holder for directing a nail through the card, and a spring clip on the top of said head with its end directed toward the nail holder for engaging the top edge of said card while a nail is driven therethrough by said head.

4. In a card attaching device, a handle, a tool head on said handle having a vertical groove adapted to receive a nail head and having adjacent thereto a holder for maintaining the nail at right angles to said tool head, and a clip on said tool head for engaging the top edge of a card while a nail is driven therethrough by said head.

5. In a card attaching device, a handle, a tool head thereon having a driving face and a holder for maintaining a nail at right angles to said face, and means for holding a card in advance of the nail point before the nail is driven, said card holding means and said nail holder being releasable after

the nail is driven, by a downward pull of the handle.

6. In a card attaching device, a handle, a tool head on said handle, a holder forming with said handle an elongated slot for the reception of a card, said holder engaging the major portion of said card, a nail holder adjacent to the face of said tool head having a slot for the reception of the body of a nail, said tool head having a slot for the head of the nail aligned with said aforementioned slot, and a clip on said tool head for engaging the top edge of the card while a nail is driven by said tool head.

15 In testimony whereof, I have hereunto signed my name at Enola, Pennsylvania, this 15th day of February, 1932.

GEORGE W. LENTZ.
